UNITED STATES PATENT OFFICE

112,213

DESIGN FOR A COMBINED FLASHLIGHT AND TROUBLE FINDING DEVICE

Isadore M. Povsner, Chicago, Ill., assignor of one-half to Walter G. King, Chicago, Ill.

Application August 8, 1938, Serial No. 79,178

Term of patent 7 years

To all whom it may concern:

Be it known that I, Isadore M. Povsner, a citizen of the United States, residing at Chicago, in the county of Cook and State of Illinois, have invented a new, original, and ornamental Design for a Combined Flashlight and Trouble Finding Device, of which the following is a specification, reference being had to the accompanying drawing, forming part thereof.

In the drawing—

Fig. 1 is a side elevational view of a combined flashlight and trouble finding device embodying my new design;

Fig. 2 is also a side elevational view thereof but looking from a different viewpoint;

Fig. 3 is a top plan view thereof; and

Fig. 4 is a view taken along the section line 4—4 of Fig. 2 looking in the direction indicated by the arrows.

I claim:

The ornamental design for a combined flashlight and trouble finding device, substantially as shown.

ISADORE M. POVSNER.
